TRANSPARENT CASE FOR A FLAG OR THE LIKE

Wilmer E. Ehle, 609 E. Main St., Stoughton, Wis.

Filed May 14, 1962, Ser. No. 70,114

Term of patent 14 years

(Cl. D58—2)

FIG. 1

FIGURE 1 is a top plan view of a transparent case for a flag or the like embodying my new design;

This application is a continuation-in-part of my co-pending application Serial No. D. 60,063, filed April 6, 1960, and now abandoned.

I claim:

The ornamental design for a transparent case for a flag or the like, as shown and described.
